(57) **CLAIM**

The ornamental design for a container with lid as shown and described.

DESCRIPTION

FIG. 1 is a top, front, right perspective view of a first embodiment of a container with lid, showing my new design, shown with the lid open.

FIG. 2 is a bottom, rear, left perspective view thereof.

FIG. 3 is front view thereof.

FIG. 4 is a rear view thereof.

FIG. 5 is a top view thereof.

FIG. 6 is a bottom view thereof.

FIG. 7 is a left view thereof.

FIG. 8 is a right view thereof.

FIG. 9 is a top, front, right perspective view of the first embodiment of the container with lid, showing my new design.

FIG. 10 is a bottom, rear, left perspective view thereof.

FIG. 11 is front view thereof.

FIG. 12 is a rear view thereof.

FIG. 13 is a top view thereof.

FIG. 14 is a bottom view thereof.

FIG. 15 is a left view thereof.

FIG. 16 is a right view thereof.

FIG. 17 is a top, front, right perspective view of a second embodiment of a container with lid, showing my new design, shown with the lid open.

FIG. 18 is a bottom, rear, left perspective view thereof.

FIG. 19 is front view thereof.

FIG. 20 is a rear view thereof.

FIG. 21 is a top view thereof.

FIG. 22 is a bottom view thereof.

FIG. 23 is a left view thereof.

FIG. 24 is a right view thereof.

FIG. 25 is a top, front, right perspective view of the second embodiment of the container with lid, showing my new design.

FIG. 26 is a bottom, rear, left perspective view thereof.

FIG. 27 is front view thereof.

(Continued)

FIG. 28 is a rear view thereof.

FIG. 29 is a top view thereof.

FIG. 30 is a bottom view thereof.

FIG. 31 is a left view thereof; and,

FIG. 32 is a right view thereof.

The broken lines in the figures illustrate portions of the container with lid that form no part of the claimed design. Break lines having a jagged element illustrate that no particular length of the portion is claimed and form no part of the claimed design. The appearance of any portion between the break lines forms no part of the claimed design.
